UNITED STATES PATENT OFFICE.

HARRY W. NEAL, OF INDIANAPOLIS, INDIANA.

REGISTER-SHIELD.

1,152,539.

Specification of Letters Patent.

Patented Sept. 7, 1915.

Application filed February 13, 1915. Serial No. 8,001.

To all whom it may concern:

Be it known that I, HARRY W. NEAL, a citizen of the United States, residing at Indianapolis, in the county of Marion and 5 State of Indiana, have invented a new and useful Register-Shield, of which the following is a specification.

My invention relates to register shields.

It is the object of my invention to make a 10 register shield with a water pocket located in the most convenient and advantageous position, and to do so at a minimum of expense; and to provide in this register shield an efficient dirt-catching pocket. 15 In carrying out my invention, I provide a register shield which has two end walls, preferably of cast metal, in which are formed integral water pockets opening both inside and outside of the register shield, or 20 on both sides of the end walls; and mount on these end walls a curved reflector plate, which is conveniently of sheet metal, which at its forward and upper end is bent downward and rearward to form a pocket for 25 catching the dirt carried by the hot air from the register.

The accompanying drawing illustrates my invention.

Figure 1 is a perspective view of a register 30 shield embodying my invention, showing it in place over a register; Fig. 2 is an elevation of one of the end members of this register shield; and Fig. 3 is a sectional perspective view of such end member, the section being taken substantially on the line 3-3 of Fig. 2.

The register shield comprises two duplicate end members 10, which are formed of cast metal with a peripheral flange 11 for 40 purposes of strength and beauty, these end members being provided with a flat base 12 for resting on the floor and with an upwardly and forwardly curved rear edge 13, which conforms to the desired shape of the 45 deflector plate 14 which extends from one end member 10 to the other and forms the rear member of the register shield. This deflector plate 14 is conveniently of sheet metal, and is fastened in any suitable manner 50 to the end members 10, and at its forward and upper end is curved downwardly, rearwardly, and then upwardly to form a pocket 15 which will catch and retain a large part of the dust particles which are 55 carried by the ascending currents of air

from the register 16. The shape of this pocket conforms to the shape of the upper and forward ends of the end members, as shown in Fig. 2.

Each end member 10 has formed in it a 60 water pocket 20, which is formed by making the lower part of such body portion of two laterally displaced walls 21 which join at the bottom and the front and rear with such body but are separated at their upper edges 65 from the body of the end member by openings 22 on both sides. These openings 22 permit the pockets 20 to be filled at the outer sides of the end members, and allow evaporation both on the outer sides and the inner 70 sides of such end members, the evaporation on the inner sides serving to humidify the rising current of air from the register 16.

I claim as my invention:

1. A register shield, comprising a pair of 75 end members of cast metal having water pockets formed in them and integral with their bodies, which water pockets open on both the inner and outer sides of such end members, and a deflector plate which is 80 curved to produce the desired deflection and connects the two end members, said deflector plate being of sheet metal.

2. A register shield, comprising a pair of 85 end members having water pockets formed in them, which water pockets open on both the inner and outer sides of such end members, and a deflector plate which is curved to produce the desired deflection and connects the two end members. 90

3. A register shield, comprising a pair of end members having water pockets formed in them, which water pockets open on both the inner and outer sides of such end members, and a deflector plate which is curved to 95 produce the desired deflection and connects the two end members, said deflector plate at its forward end being curved downwardly, rearwardly, and upwardly, so as to form an inwardly opening pocket so as to catch dirt 100 particles carried by the stream of air deflected thereby.

In witness whereof, I have hereunto set my hand at Indianapolis, Indiana, this eighth day of February, A. D. one thousand 105 nine hundred and fifteen.

HARRY W. NEAL.

Witnesses:

JOSEPHINE GASPER,
LOUISE BENNETT.
